UNITED STATES PATENT OFFICE

2,119,844

FASTENER

Daniel A. Brennan, Chicago, Ill.

Application October 4, 1937, Serial No. 167,094

7 Claims. (Cl. 24—153)

The invention relates to improvements in fasteners for binding papers together in a sheaf, such as letters in a file, including a base having spaced prongs adapted to extend through apertures in the papers and a compressor having similarly spaced apertures adapted to receive said prongs, the end portions of the latter being adapted to be bent downwardly against said compressor and to be held securely in bent position.

5 Paper fasteners of the type comprising a base having prongs adapted to pass through apertures in a sheaf of papers and a compressor having registering apertures adapted to receive said prongs, in some instances, are provided with

10 latches slideable over the prongs after the latter are bent downwardly substantially against the compressor. In such devices, the latches are, in some instances, arranged to slide inwardly over the prongs from a position outwardly of the apertures and in other instances said latches are slideable outwardly over the prongs from a position intermediate the apertures.

The invention relates primarily to a novel construction of either type of fastener embodying slideable latches to detachably engage means in the prongs to prevent inadvertent shifting of the latches off from the bent over prong portions. The novel means incorporated in this invention differ materially from the means shown, described and broadly claimed in my co-pending application, Serial No. 476,058, filed August 18, 1930, wherein means has been provided on the prong ends for engaging in recesses or apertures in the latches to prevent inadvertent shifting of said latches.

The specific structure herein disclosed, for preventing inadvertent shifting of the latches off from the ends of the prongs, is novel means on the prongs to embracingly engage the latches, which means is fully disclosed and broadly claimed in my co-pending applications, Serial No. 688,099, filed September 5, 1933; and Serial No. 22,291, filed May 20, 1935. The present application is a continuation-in-part of said co-pending applications.

It is therefore, an object of the present invention to provide an improved paper fastener with novel means for effecting a yieldable latching or embracing engagement between the prongs and the latches resisting displacement after the latter are moved into position to hold the prongs in bent down position over the compressor.

Another object is to provide a base for paper fasteners with novel means at its ends adapted

for co-operative engagement with means associated therewith.

Another object is to provide an improved fastener which is inexpensive to manufacture, simple in operation and efficient in use.

The foregoing and such other objects of the invention as will more fully appear hereinafter as the description proceeds will be more readily understood from a perusal of the following specification, reference being had to the accompanying drawing, in which:

Fig. 1 is a plan view of a fastener embodying features of the invention, showing one latch partially broken away.

Fig. 2 is a fragmentary longitudinal sectional view taken on line 2—2 of Fig. 1.

Fig. 3 is a plan view of a fastener embodying a modified construction.

Fig. 4 is a fragmentary longitudinal sectional view taken substantially on line 4—4 of Fig. 3.

In the various embodiments illustrated like numerals identify like parts.

Referring particularly to Figs. 1 and 2, the fastener constituting one embodiment of the invention comprises a base 11 having bendable prongs 12 at opposite ends, and an elongated compressor 13 having spaced apertures 14, one inwardly of each end, adapted to receive the prongs. Elevated parallel guides or flanges 15 are provided along the opposite longitudinal edges of the compressor 13. Preferably, the guides 15 are formed by folding the marginal side edges of the compressor 13 upwardly and then outwardly, as shown, and said guides may extend beyond the apertures 14. The guides 15 serve to reinforce the compressor 13 and to confine the prongs 12 laterally when the latter are bent downwardly over the top face of the compressor.

In this form of fastener, the projecting ends of the prongs 12 may be bent down against the compressor either inwardly or outwardly from the apertures 14. Stops 16, formed by striking detents downwardly, are provided at each end of each guide 15. Two latches 17, each preferably formed of a strip of metal extending transversely of the compressor 13, are mounted to slide along the guides 15 between the stops 16.

While the prongs are bent over inwardly towards each other, as shown, the latches 17 may be initially located inwardly of the ends of the downwardly bent prongs and are then movable outwardly toward the apertures over the ends of said prongs to hold the latter bent over the compressor 13. If desired, the latches may be initially positioned outwardly of the apertures 14,

as indicated in dotted lines, for movement inwardly towards each other over the bent over ends of the prongs. This latter arrangement is extremely desirable should a base having extremely long prong be used. In this event the long prongs overlap each other a considerable distance when a comparatively thin sheaf of papers is bound.

The latches 17 are provided, on their ends, with inwardly turned shoe portions 18 embracing the flanges 15. Each prong 12 preferably is provided with two longitudinally spaced apart upwardly extending transverse projections or ribs 19 defining opposed shoulders 21. The portion of the prong between the shoulders provides a recess or compartment 22 to receive the bridge-like portion of one of the latches 17 when the latter is moved into latching position therewith. Longitudinal shifting of the latches is prevented by the embracing engagement of the shoulders 21 with the edges of said latches and the inherent resiliency of the underlying prong is sufficient to retain each latch yieldingly in latching position within the recess or compartment 22.

The form of fastener shown in Figs. 3 and 4 and also shown in my said co-pending application, Serial No. 688,099, differs from the form previously described in that the latches 17 are adapted to be restrained from moving outwardly of the apertures by stops 16 formed at each aperture 14 preferably by depressing the longitudinal inwardly turned side flanges 15, as shown. The latch is substantially like that previously described except that it does not embrace the longitudinal flanges 15a but has shoe portions 18a sliding between the top face of the compressor 13a and the flanges. Inadvertent sliding of the latches off from the downwardly bent end portions of the prongs 12a is prevented by providing two longitudinally spaced apart projections 19a on each prong, between which the respective latch is adapted to be positioned. As best shown in Fig. 4, the inherent resiliency of the underlying prong retains the projections 19a in engagement with the opposed edges of the latch 17a embraced thereby and said latches can only be shifted upon forcibly depressing the prong ends to disengage the projections 19a from said latches.

In the fasteners shown herein novel means is provided on the prong to prevent inadvertent shifting of the latch off from the underlying prongs, and the latches may be initially positioned inwardly of the bent down prongs in either form, and in the fastener illustrated in Figs. 1 and 2, the prongs may be bent and secured either inwardly or outwardly of the apertures.

Although exemplary forms of the invention have been described in detail in the foregoing specification and illustrated in the accompanying drawing it is not desired to limit the invention to the precise forms of fasteners disclosed but to embrace such modifications thereof as will

fall within the spirit of the invention and the scope of the appended claims.

I claim:

1. A base for a paper fastener comprising an elongated body portion and substantially flat bendable spaced prongs joined at one end to said body portion, each of said prongs being provided adjacent its other end with upstanding projections spaced apart lengthwise of the prongs. 5

2. A fastener comprising a base having one or more bendable securing prongs; a compressor co-operating therewith and held in position thereby; a latch slideable on said compressor and over a prong in bent position; and upstanding projections on said prong engaging opposite edges of said latch and releasably holding the same from sliding on said compressor in either direction. 15

3. A fastener comprising a base having one or more bendable securing prongs, a compressor co-operating therewith and held in position thereby, and a latch slideable on said compressor and over a prong in bent position, said prong being formed adjacent its end to engage opposite edges of said latch to releasably hold it from sliding on said compressor in either direction. 25

4. A fastener comprising a base having one or more bendable securing prongs, a compressor co-operating therewith and held in position thereby, and a latch slideable on said compressor and over a prong in bent position, said prong being formed adjacent its end to engage opposite edges of said latch to positively hold it by the inherent resiliency of the prongs from sliding on said compressor in either direction. 30

5. A fastener comprising a base having a bendable securing prong at each end thereof, a compressor co-operating therewith and having spaced apertures for the reception of said prongs, two latches slideable on said compressor and over the ends of said prongs in bent positions, and upstanding projections on each of said prongs engaging opposite edges of the corresponding latch and releasably holding the same from sliding on said compressor in either direction. 40

6. A fastener comprising a base having one or more bendable securing prongs, a compressor co-operating therewith and held in position thereby, and a latch slideable on said compressor and over a prong in bent position, said prong being formed adjacent its end to provide a compartment adapted to receive said latch and releasably hold the same from sliding on the compressor in either direction. 50

7. A base for a paper fastener comprising an elongated body portion and substantially flat bendable spaced prongs joined at one end to said body portion, each of said prongs having longitudinally spaced apart transverse shoulders adjacent its other end. 55
